*R. French,
Making Augers,
Patented Nov 11, 1834.*

Raymond French.
Letters Patent dated November 11, 1854

The schedule referred to in these Letters Patent and making part of the same, containing a description in the words of the said Raymond French, himself of his improvement in Screw, Spur and pump Augers, screw & spur bits.

To all to whom these presents shall come.

Be it known that I, Raymond French, of Derby in the County of New Haven and State of Connecticut, have invented a new and useful improvement in the form and construction of screw, spur & pump Augers, screw & spur bits; & that the following is a full and exact description of the construction and operation of the said instruments, as invented or improved by me.

[The plates from which the rods are formed, are constructed of a longitudinal concave surface, or in any other manner, so that the plate as well as the rod when twisted shall be thinner in the centre and middle than upon its edges. This may be effected by a regular concavity from one edge to the other, upon each of its sides (see plate N° 1) or by an obtuse angle from the longitudinal centre to the edges (see plate N° 2), or by an even plate in the middle varying in width according to the dimensions of the plate, and elevated or thickened upon the edges (see plate N° 3).] In general about one inch of the lower extremity of the plate is of the usual construction, that is to say of even thickness, for the purpose of raising and strengthening the lips of the screw.

The middle of the plate is to be made as thin as possible and retain its position in the process of manufacturing the same as well as retaining it only when applied

292
to use; being generally about one sixteenth part of inch thick
in a plate of one inch in length and varying with the size
of the plate as well as the part of metal. The edges of a plate
of one inch breadth, are to be made generally about three
eighths of an inch thick varying still with the breadth of
the plate (See illustration) and when so made the edges
are formed, in other respects in the usual manner.

The improvement by this method of constructing
the plate is that it gives the spiral of threads of the tool
when twisted, a greater capacity to pull the metal sur-
face of the plate and so more perfectly envelops the
core or shank within a metallic surface in the passage
from the bottom to the top of the hole while boring,
by which the shank is well protected to the end of the
bore and the tool being prevented by a great
degree from friction upon the surface of the hole, and from
clogging within the tool. It can be seen more clearly from the
tool constructed in the manner, than in the usual form,
and the strength and durability of the instrument are increased
by abiding the principle part of the metal, more compactly from
the axis or longitudinal centre of the instrument.

In short all I claim as my invention in the foregoing im-
provement, is the principle and its application to every construc-
tion of the plates and tool of screw augers and bolts thicker
upon the edges than in the middle, and the mod-
ifications and all the same as are specified, and
that the same principle and form may be applied
to all tools used for boring holes in wood or timber
having a transverse passage, and so prevent clogging
of the tool.

John Clark Wheeler Esq. Raymond French
Attala Co. Tenn. 1845.

Received and recorded April 10, 1845.
